UNITED STATES PATENT OFFICE

FAY E. BOSS, OF MILAN, MICHIGAN

FURNACE

Application filed June 5, 1931. Serial No. 542,378.

This invention relates to heating furnaces for use in warm air systems.

Heretofore warm air furnaces have been formed generally either of castings or of sheet steel. Cast furnaces usually consist of several major parts held together by their weight and requiring the use of extensive joints sealed with furnace cement. The cement deteriorates and causes the furnace to 10 leak gas and smoke unless the structure is torn down and re-cemented every two or three years. Cast furnaces are also objectionable because the direct contact of live coals with the fire pot and feed section causes these 15 portions to burn out quickly. A further objection is found in the location of the hottest part of the furnace near the base. With the intense heat so low in the furnace the movement of cold air in the cold air ducts is restricted and the efficiency of the furnace is 20 greatly impaired.

Furnaces made of steel have been objectionable because the radiators have been stationary relative to the furnaces proper and, 25 consequently, it has been necessary for the smoke to pass out always at the back or at some other point determined prior to manufacture. The radiator is usually a long, transversely curved member connected to the 30 furnace or drum with a smoke pipe formed of steel and cast iron. This radiator usually extends from the top of the drum portion of the furnace to a point near the bottom thereof and, because of its location all of the 35 heat becomes concentrated in the back of the furnace, causing the heat pipes in front of the furnace to heat poorly. Other disadvantages resulting from the use of a radiator of the type mentioned are interference with 40 the free circulation of air through the cold air ducts, rapid deterioration of the metal forming the radiator due to the chemical reaction set up between the moisture and soot during the summer months, and the difficulty 45 experienced in cleaning the radiator which can be accomplished solely by removing the smoke pipe.

The present invention has for an object the 50 elimination of all of the faults present in the two types of furnaces mentioned while at the

same time retaining those advantages present in such furnaces.

It is a further object to provide a furnace which can be manufactured readily, is provided with gas tight joints which will not 55 deteriorate, has a radiator adjustable to several different positions, and provides the hot spot of the furnace at a point a considerable distance above the furnace bottom.

A still further object of the invention is 60 to provide a furnace the body or drum portion of which is formed of sheet steel lined with fire brick in the fire pot while the radiator is formed of cast iron in one piece, this being desirable because a cast iron radi- 65 ator will last indefinitely.

Another object is to provide the furnace with a means for directing air to a point above the fire pot and below the radiator where it will increase combustion and the 70 intensity of the heat, this air being supplied to the point of use in a simple and efficient manner without complicating the furnace structure to an objectionable extent.

Another object is to provide a radiator of 75 novel construction with which is combined improved means for controlling the flow of hot gases through the radiator.

With the foregoing and other objects in view which will appear as the description 80 proceeds, the invention resides in the combination and arrangement of parts and in the details of construction hereinafter described and claimed, it being understood that changes in the precise embodiment of the invention 85 herein disclosed may be made within the scope of what is claimed without departing from the spirit of the invention.

In the accompanying drawings the preferred form of the invention has been shown. 90

In said drawings:

Figure 1 is a central vertical section through the furnace, the outer casing being removed.

Figure 2 is a plan view of the radiator. 95

Figure 3 is a plan view of the body of the furnace, the radiator being removed.

Figure 4 is an enlarged section through the joint between the radiator and the frusto- 100 conical upper end of the furnace body.

Referring to the figures by characters of reference 1 designates a cylinder of sheet steel closed at the bottom by a head 2 welded therein while to the upper end of this cylinder is welded a frusto-conical extension 3. A lower opening 4 is formed in the wall of the cylinder and has a chute 5 welded therein and extending outwardly therefrom. This chute thus opens into the ash pit 6 provided 10 in the lower portion of the cylinder below grate 7 which can be of any desired construction. The fire pot 8 provided above the grate is walled with firebrick 9 suitably supported, as by a ring 10 secured within the 15 cylinder, and opening into the cylinder above the fire pot is a feed chute 11 welded thereto and extending outwardly therefrom.

The front of the furnace has been indicated at 12 and is cast with openings 13 and 20 14 in which are seated the outer ends of the chutes 5 and 11 respectively. A water pan 14 can be carried in the upper portion of front 12 and that part of the front above the water pan can be extended forwardly as 25 at 15 and provided with an opening 16 normally closed by a clean-out door 17. An ash-pit door has been indicated at 18 and has the usual hinged draft door 19.

The fuel door has been indicated at 20 and 30 is hingedly connected to the front 12 so as to normally close chute 11. This door has a lining 21 spaced inwardly from the front portion so as to provide an air space 22. An air inlet 23 is provided in the bottom portion 35 of the door and opens into this space. A steel flue plate 24 is secured across chute 11 near the top thereof and its outer edge is adapted to lap the upper edge of lining 21 when door 20 is closed. Thus a continuous 40 fresh air flue will be provided extending from the inlet 23 upwardly within door 20 and inwardly above plate 24. The air flowing above the plate will be delivered into the frusto-conical extension 3 so as to mix thoroughly 45 with the hot products of combustion in the throat formed by the extension. The hot blast thus produced will act to maintain a very high temperature in the upper portion 50 of cylinder 1, the extension 3 and the radiator hereinafter described.

Fitted tightly in the upper portion of extension 3 is an inner ring 25. An outer ring 26 is fitted tightly on the outer surface of extension 3. These rings after being wedged 55 into engagement with the extension are fastened thereto by bolts 27. Ring 26 has an annular flange 28 at its upper edge and this flange provides a seat for a continuous gasket 29 formed preferably of asbestos.

60 Resting on the gasket 29 is the frusto-conical central portion 30 of the cast radiator 31. This central portion has ears 32 extending from the base thereof and adapted to be supported above similar ears 33 extending from 65 flange 28. The ears 32 are regularly spaced

and the ears 33 are similarly spaced. Thus the radiator 31 can be adjusted annularly relative to cylinder 1 to several different positions and when it is in any of these positions it can be securely fastened by bolts 34.

Obviously by tightening bolts 34 the radiator casting will clamp the gasket 29 tightly on its seat so that no leakage of gas or smoke can take place.

The radiator has a frusto-conical recess 35 which opens downwardly into the extension 3 and opens at diametrically opposed points into flues 36 and 37 which maintain communication with a circular flue 38 concentric with the central portion 30. A clean out extension 39 extends outwardly from flue 38 opposite flue 36 and is seated in the opening 16 where it is normally closed by the door 17. A smoke flue 40 extends from flue 38 opposite flue 37 and is adapted to be connected with a chimney. Extending transversely of the smoke flue is a small shaft 41 provided at its outer end with an operating arm 42. A crank arm 43 is extended from the shaft at a point within flue 40 and is connected by a link 44 to a centrally fulcrumed damper 45 mounted in flue 37. This damper is adapted to move against stops 46 when brought to closed position.

It is to be understood that any suitable means may be provided for automatically or otherwise operating door 19 and damper 45 in unison.

It will be noted that the radiator is formed in one casting. Smoke and gases are drawn into the recess 35 and then passed through flue 36 after which they are divided and pass in opposite directions through opposed portions of flue 38 to the outlet or smoke flue 40. As the flue 38 is extended below the top of extension 3 it acts to deflect air at a high velocity through the arcuate spaces 47.

The action of the air in flowing at a high velocity through the passages 47 tends to cool the extension 3 and to keep it from deteriorating.

Importance is attached to the provision of means for conducting fresh air into the upper portion of cylinder 1. The lining of the door is very hot and the same is true of the plate 24. Thus the air flowing therealong will be preheated to a high temperature and will be delivered as a hot blast to the combustion chamber several inches above the fire. Consequently combustion will be rendered more efficient. Furthermore the air entering the combustion chamber at the base of extension 3 further serves to keep down the temperature of said extension.

By providing the damper 45 the combustion products can be allowed to flow directly to flue 40 simply by opening the damper. This is especially desirable when starting a fire, when adding fuel, and when burning a low grade of fuel.

As the radiator is adjustable annularly, the smoke flue 40 can be brought to any desired position to make the best possible connection with the chimney.

- 5 The upper edge of the frusto-conical extension 3 is preferably cut off square as indicated so as to provide a slightly projecting annular rib 48 which will press into gasket 29 and render its sealing action more efficient.
- 10 While the outer ring 26 has been shown attached to extension 3 by bolts it is to be understood that it can be welded thereto if so desired.

What is claimed is:

- 15 1. A warm air furnace including a sheet metal body, having a frusto-conical extension, inner and outer rings wedged against the top portion of the extension, the outer ring constituting a seat, and a cast metal radiator supported upon said seat and adjustable angularly relative thereto, said radiator opening into the extension.
- 20 2. A warm air furnace including a sheet metal body having a frusto-conical top extension, rings wedged against the inner and outer faces of the extension at the top thereof to provide a seat, a sealing gasket supported by the seat, a cast metal radiator mounted on the gasket and opening into the extension, and regularly spaced means engaging the radiator and one of the rings for securing the radiator to the extension for angular adjustment relative thereto.
- 25 3. A warm air furnace including a sheet metal body, having a frusto-conical extension, inner and outer rings connected to the top portion of the extension, the outer ring constituting a seat, and a cast metal radiator supported upon said seat and adjustable angularly relative thereto, said radiator opening into the extension.
- 30 4. A warm air furnace including a sheet metal body, having a frusto-conical extension, inner and outer rings connected to the top portion of the extension, the outer ring constituting a seat, and a cast metal radiator supported upon said seat and adjustable angularly relative thereto, said radiator opening into the extension.
- 35 50 In testimony that I claim the foregoing as my own, I have hereto affixed my signature.

FAY E. ROSS.
